U.S. Cl. D87—1 R

FIG. 1

FIG. 2

FIG. 1 is a perspective view of a pen case with pen in a closed condition, showing my new design; and

FIG. 2 is an enlarged perspective view thereof in the open condition.

The side of the container opposite the side shown in FIG. 1 is identical in appearance to that shown in FIG. 1 apart from the absence of the finger recesses. The bottom is identical in appearance to the top.

I claim:

The ornamental design for a pen case with pen, as shown and described.
